UNITED STATES PATENT OFFICE.

OTTO HEINIGKE, OF NEW Utrecht, NEW YORK, ASSIGNOR TO THE HARTFORD CARPET COMPANY, OF HARTFORD, CONNECTICUT.

DESIGN FOR A CARPET.

SPECIFICATION forming part of Design No. 18,155, dated March 6, 1888.

Application filed January 26, 1888. Serial No. 262,086. Term of patent 3½ years.

To all whom it may concern:

Be it known that I, OTTO HEINIGKE, of New Utrecht, Long Island, New York, have invented a new and original Design for Carpets, of which the following is a specification, reference being had to the accompanying photograph, which forms a part of the same.

The invention relates to a design to be worked into or upon surfaces, such as carpets or similar fabrics; and it consists in the novel configuration and grouping of figures herein specifically shown and claimed.

The accompanying photograph is a face view of a carpet showing my new design.

15 The characteristic feature of my design is the figure A, which is repeated at intervals

over the face of the carpet. The figure A is circular in shape, and is composed of conventionalized flower and leaf forms having small spaces intervening between them. These figures are disposed upon a damask ground.

What I claim as new, and desire to secure by Letters Patent, is—

1. The design for carpets, consisting of the figure A, substantially as shown.
2. The design for carpets, consisting of the figures A and the damask ground, substantially as shown.

OTTO HEINIGKE.
